UNITED STATES PATENT OFFICE.

ALFRED RICHARDSON, OF NELSONVILLE, OHIO.

CLEANER FOR STEAM BOILERS.

Application filed April 28, 1926. Serial No. 105,282.

This invention relates to cleaners for steam boilers. It is a well known fact that in all boilers where water is employed for generating steam, that a certain quantity of foreign matter is carried in suspension in the water and deposited upon the bottom of the boiler in the form of mud. This accumulation of mud not only covers the bottom of the boilers, but also the tubes and other parts so that such parts are insulated and thereby prevents the heat from being conducted through the same. The present practice for removing such mud provides for a draw off through the bottom of the boiler from which the water is withdrawn, but only a small quantity of the mud is removed in this manner. General cleaning takes place about every two weeks because of the fact that the boiler must be cooled. In order that the boilers may be in readiness for operating, the cleaning must be done on Sunday.

It is an object of the present invention to provide a device whereby the mud or foreign matter may be removed daily without interruption of the production of steam.

A further object of the invention is the provision of a device having a plurality of flat pipes which are disposed between rows of the usual tubing mounted in a boiler, and through which flat pipes the mud and water are forced by means of the usual steam pressure in the boiler.

A further object of the invention is the provision of a device having a plurality of tubes depending from a common discharge pipe, with the tubes having open ends terminating adjacent the bottom of the boiler, with the valve mechanism controlling the opening of each tube, whereby the discharge of water and mud from the boiler is limited at will.

This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient features of the invention as expressed in the appended claims.

In the drawings:—

Figure 1 is a longitudinal vertical section 55 of a boiler showing my cleaning device in operative position in the boiler.

Figure 2 is a transverse vertical section taken along the line 2—2 of Figure 1,

Figure 3 is a fragmentary enlarged detail 60 view showing the valve mechanism controlling successively the discharge of each of a plurality of vertically disposed pipes, and

Figure 4 is a fragmentary transverse vertical section showing a detail of the connection between the vertically disposed pipes 65 and the valve casing from which the pipes are suspended.

Figure 5 is a fragmentary vertical section showing the valve operating means disclosed 70 in plan in Figure 3.

Referring more particularly to the drawings 10 designates a boiler having a steam space 11 above the water level 12. The boiler, as is usual, has a plurality of horizontally arranged pipes 13 connected with the heads 14 and 15, at the opposite sides of the drum and through which a heating medium is forced to heat the water in the boiler 10. 75

Running longitudinally of the boiler and located above the top row of the horizontally disposed pipes 13 is a casing 16 in which is rotatably mounted a pair of cylindrical valves 17 and 18. These valves are made in sections and joined together by inter-engaging fingers 19. Spaced at intervals along each section and circumferentially of the valves are a plurality of ports 20 which are arranged spirally in the valves. The casing 90 80 85 95 100

16 is also provided with openings 21 along the lower edge and alining with each of the ports 20 successively as the valve is rotated. A plurality of pipes 22 depend from the casing 16 and each pipe is connected to 95 said casing by means of a pair of arms 23 which embrace the casing 16 at diametrically opposite points. These arms are locked together by means of a key 24 passing through perforations 25 in said arms 23. 100 The key 24 is provided with a notch 26 at each end 26^a to engage that portion of the arm which is at the upper edge of one of the openings 26. The key is cut out, as shown at 27, in order to snugly engage 105 over the top of the casing 16, as the arms 23 are drawn towards each other, and the key 24 is slipped in place for locking the clamp-

ing arms in rigid engagement with the casing 16. The arms, as shown at 28, conform to the curvature of the casing 16 so that the upper end of each pipe 22 will snugly fit 5 said casing and seal the pipes from the passage of fluid at this point.

It will be noted that the pipes 22 gradually increase in cross sectional area until they reach a point adjacent the bottom 29 of the 10 boiler. The tubes, it will be noted, have the four walls flat instead of circular, as in the ordinary form of pipes, and the gradually increasing cross sectional area of the pipes provides for an expansion of the lower 15 end so that the water and mud from the bottom of the boiler may be readily forced into the pipes for discharge.

The valves 17 and 18 are simultaneously rotated by means of a gear 31 secured to the 20 valves and located between a pair of plates 32 which are loose on the valves 17 and 18 and adapted to be revolved thereon. A pawl 50 pivoted at 51 on extensions of the plates 32 is maintained in engagement with 25 gear 31 by a weighted arm 52 integrally formed with the pawl. One end of a link 54 is connected at 53 with the plates 32. The other end of the link has a slotted connection 55 with a pin 56 carried by a disc 57. 30 The disc is manually rotated by a shaft 58 and hand wheel 59, the shaft being mounted in bearing 60 on the boiler 10.

A discharge pipe 34 is connected to the casing 16 and the valve 17 is provided with 35 ports 35 in order that the fluid within the valve may readily pass through the pipe 34, and through the discharge pipes 36 and 37, and thence to the atmosphere. The valve 38 controls the discharge of the water 40 through the pipes 34 and 36. A second discharge pipe 39 is connected with the casing 45 and is in open communication with the cylindrical valve 18 through a plurality of ports 35^a whereby water passing through said valve may be discharged past valve 40 and to pipe 37, and thence to the atmosphere.

The valve 40 controls discharge of water through pipe 39 and valve 18 and is adapted to be opened for cleaning the boiler when the 50 valve 38 is closed.

A pipe 45 is connected with the bottom 29 of the boiler 10 at one end and a valve 46 is adapted to open and close said pipe to the common discharge pipe 47. The pipe 45 55 is the pipe by which it is attempted to clean the boiler at the present time. The ends of the valves 17 and 18 are provided with closures 50.

The operation of my device is as follows: 60 When it is desired to clean the boiler of mud and other foreign material, one of the valves such as 38 is opened and pressure of the steam in the boiler 10 forces the water and the mud in the bottom of the boiler into 65 the flaring mouth of a vertically disposed

stand pipe 22. At this time, the hand wheel 59 is rotated whereby the valves 17 and 18 are revolved and the consecutive ports 20, which are spirally arranged, register successively with the ports 21 in the casing 16 so that the successive pipes 22 are opened to the boiler and a constant stream of mud and water is being progressively removed from the bottom 29 of the boiler. This water and mud pass outwardly through the pipes 22 70 through the valve 17, through pipe 34 and pipes 36 and 37 through the outlet 47. Any form of dial (not shown) may be placed adjacent the hand wheel 59 to indicate when the last of the series of pipes 22 have been 75 opened to the valve 17 and the hand wheel is rotated so that all of the ports 20 of the valve 17 are closed to any of the stand pipes connected with said valve.

Valve 38 is then closed and valve 40 is 80 opened and the hand wheel 59 is again rotated in order to successively place the stand pipes 22 connected with the valve 18, in communication with the discharge pipe 39, so that the water may be progressively 85 drawn from the second section of the boiler. It will be appreciated that the steam from the boiler causes the water in said boiler to rise in the stand pipe, which has been 90 opened to the bottom of the boiler through pipe 39. The water flows past valve 40 through pipe 37 and is discharged at 47. If necessary the operation may be repeated 95 until the engineer is satisfied that all the mud has been cleaned from the boiler. It 100 will be noted that the successive currents of water passing through the stand pipes 22 come from the whole section all along the bottom of the boiler so that the mud and 105 water from this portion of the boiler will be removed through the successive stand pipes which supply a constant stream of the mud and water to the pipes 36 and pipe 37 after 110 which the mud and water are discharged to the atmosphere. By this construction it is 115 unnecessary to wait until the boiler has cooled since steam pressure in the boiler is required for cleaning the boiler of mud and foreign matter. By this construction the 120 boiler may be cleaned daily without any 115 interference with the usual running of the factory.

By my improved construction the mud 125 may be removed every day without interfering with the operation of the boiler so that the mud will not boil up over the tubes and inner wall of the shell and thus be kept in continuous circulation. When the mud is not removed, a new deposit of mud is being continuously formed on the 130 tubes and shell, thus retarding heat penetration and causing clogging of the bottom of the boiler. The accumulation of mud finally requires expensive repairs to the boiler and often loss of service so that by 135

employing my device a large saving of labor and materials, particularly in gaskets, is had.

What I claim is:—

1. In a boiler, means for removing mud from the bottom of the boiler comprising a valve casing extending the length of the boiler, pipes suspended from the valve casing and in open communication with the same, a pair of rotary valves in the casing and provided with spirally arranged and spaced ports, said casing having spaced openings with which the ports in the valves are adapted to be alined, a gear located between the valves and secured thereto, discharge pipes connected with the casing and in open communication therewith, said valves having openings for placing the said valves in open communication with the discharge pipes where said pipes are connected to the casing, a pair of plates rotatably mounted on the adjacent ends of the valves, a weighted pawl pivotally mounted on the plates and adapted to engage the gear, and means for rocking the plates for causing rotation of the valves.
2. In a boiler, means for removing mud from the bottom of the boiler comprising

a casing extending the length of the boiler, pipes suspended from the casing and in open communication with the same, a pair of rotary valves in the casing and provided with spirally arranged and spaced ports, said casing having spaced openings with which the ports in the valves are adapted to be alined, a gear located between the valves and secured thereto, discharge pipes connected with the casing and in open communication therewith, said valves having openings for placing the said valves in open communication with the discharge pipes where said pipes are connected to the casing, a pair of plates rotatably mounted on the adjacent ends of the casing, a weighted pawl pivotally mounted on the plates and adapted to engage the gear, and means for rocking the plates for causing rotation of said gear to turn said valves, the pipes depending from the casing having their upper ends split forming a pair of flanges embracing the casing, said flanges having alined passages, and keys inserted in the passages for clamping the flanges snugly to the casing.

ALFRED RICHARDSON.
